UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR FOR REGULARLY MOVING TRANSFERRER ARMS.

Application filed August 6, 1926. Serial No. 127,698.

This invention relates to improvements in weft detectors of the type mounted on regularly moving transerrer arms for weft replenishing looms and it is the principal object of the invention to provide simplified means for restoring both the weft detector and the carrier therefor to normal position.

In copending application Serial #120,491 there is shown a transerrer arm having pivotally mounted thereon a carrier lever which supports a side slipping weft detector. In that application there are shown two separate springs, one acting on the carrier lever to raise the same to normal position and the other connected to the carrier lever and the detector to move the latter to normal position. It is an important object of my present invention to provide a single spring so mounted that the same can be divided into two sections which will exert relatively different degrees of pressure on the carrier lever and the detector.

It is a further object of my invention to provide the carrier lever with an adjustable clip to engage the spring and separate the same in two parts, said clip being movable to vary the point at which the pressure of one section is applied to the carrier lever.

It is a still further object of my invention to provide a connection between the spring and carrier lever permitting quick adjustment of said spring, said connection having preferably a notch to receive one or another of the coils of the spring, depending upon the adjustment desired.

With these and other objects in view which will appear as the description proceeds, my invention resides in the combination and arrangement of parts hereinafter described and set forth in the claims.

In the accompanying drawings, wherein I have shown one form of my invention,

Fig. 1 is a vertical longitudinal section thru that portion of the transerrer arm which extends over and parallel to the bobbin to be detected, showing the detector in contact with a full supply of weft,

Fig. 2 is a view similar to Fig. 1 but with parts moved to indicating position,

Fig. 3 is a vertical section on line 3-3 of Fig. 2 and

Fig. 4 is an enlarged vertical section on line 4-4 of Fig. 3.

Referring to the drawings it will be seen

that I have provided a transerrer arm 10 having a portion 11 extending above and parallel to the bobbin W and having slidably mounted therein a plunger 12 formed with a shoulder 13 which receives the right hand thrust on a compression spring 14 as seen in Figs. 1 and 2. The left hand end of spring 14 bears against the web 15 thru which extends a reduced shank 16 of the plunger 12. Pin 17 is passed thru the shank and limits right hand movement of the plunger under action of the spring.

The mechanism for normally holding plunger 12 in the inoperative position shown in Fig. 1 comprises a latch 18 pivoted on a pin 19 mounted in the transerrer arm. Said latch has a hook 20 which is held in a notch 21 formed in the shank 16 by a torsion spring 22, one end of which as indicated at 23 extends over a part of the portion 11 and the other end as indicated at 24 extends over the latch 18, the intermediate portions being coiled around stud or pin 19. Said latch is provided with a depending arm 25 moved to the right from the position shown in Fig. 1 at the time of indication of substantial weft exhaustion to release the plunger.

The detector 26 has a curved yarn engaging toothed surface 27 and is pivoted as at 28 to a lever 29 which in turn is pivotally mounted for free movement on a stud 30 secured to the transerrer arm. Said lever 29 has a tail 31 which normally engages that portion of the transerrer arm which serves as a housing for the plunger 12. The detector 26 has an upstanding arm 32 provided with a series of holes 33 located at different distances from the pivot 28 and there is provided a stop screw 34 carried by the arm 32 and engaging a projection 35 formed as part of the lever 29. The matter thus far described may be substantially the same as is shown in the foresaid application and forms no part of my present invention.

In carrying out my present improvements I provide a relatively long tension spring 50 one end of which extends thru one or another of the openings 33 and the other end of which is straightened and held under a screw 51, said screw affording means to adjust the tension of the spring. The intermediate portion of the spring 50 engages a clip 52 the upper portion which is provided with a notch 53 and the lower por-

tion of which extends horizontally along a portion of the lever 29 and is formed with a slot 54 thru which extends a holding screw 55. By means of the slot and screw the 5 position of the clip may be changed relatively to arm 29 and the screw 51. One of the coils of the spring is received by the notch 53 as shown in Figs. 3 and 4, the bottom of said notch extending above a 10 straight line joining the ends of the spring, the resilience of said spring holding the selected coil in the notch. The clip serves to divide the spring in two sections A and B the tension of which can be varied by having 15 one or another of the coils of the spring received by the notch 53. A further adjustment is rendered possible by means of screw 51, and the pressure of section A on the detector can be varied by means of the holes 20 33. The bottom of the notch is spaced an appreciable distance above the pin 30 so that the section B of the spring will hold the lever 29 in raised position indicated in Fig. 1.

25 In the normal operation of the loom the transerrer arm 10 is caused to move downwardly toward the bobbin W on each detecting beat of the loom by mechanism not shown and is brought to a sudden stop when 30 arriving at the position shown in Fig. 1 relatively to the bobbin, as set forth in Patent #1,372,316. The carrier lever 29, however, being freely movable about stud 30, continues its downward movement and 35 carries the detector into contact with the weft on the bobbin. If sufficient weft is present for continued weaving, as is indicated in Fig. 1, the teeth 27 will be embedded in the yarn and movement along the bobbin will be prevented. Should insufficient weft 40 be present, however, the detector teeth will not be restrained by yarn and as they lie to one side of a vertical line passing thru the stud 28 said detector will slide along the bobbin to the position indicated in Fig. 2, engaging the arm 25 and lifting the hook out 45 of engagement with the plunger 12. The latter will move to the position indicated in Fig. 2 under influence of the compression 50 spring 14 and an indication of weft exhaustion will be given to the replenishing mechanism not shown as the transerrer arm ascends as set forth in the aforesaid patent.

55 When it is desired to render the detector rather stiff in action the number of coils in the section A can be reduced and if this results in a sluggish upward action of carrier lever 29 a corresponding adjustment of section B can be effected by screw 51. The 60 variation of the relative strengths of sections A and B can be accomplished very readily by lifting the spring out of the notch 53 and placing in the latter another of the coils of the spring.

65 From the foregoing it will be seen that I

have provided a weft detector mounted on the regularly moving transerrer arm and having a single spring operatively connected both to the detector and the carrier lever therefor in such a way as to move these 70 parts to normal raised position and being mounted and supported in such a way as to afford very ready means for adjusting the tension of the two sections A and B of the detector. Furthermore, each end of the 75 spring is adjustable so that the pressure brought to bear upon either the detector or the carrier lever may be varied without disturbing the pressure of the other end of the spring. It will also be noted that the clip 80 is adjustable along the carrier lever 29 to vary the point of application of section B to said carrier.

Having thus described my invention it will be apparent that changes and modifications may be made therein by those skilled in the art without departing from the spirit and scope of the invention and I do not wish to be limited to the details herein disclosed, but what I claim is:

1. In weft detecting mechanism for looms having a regularly moving transerrer arm, a weft detector, a carrier supporting the detector and connected to the transerrer arm for relative movement therewith and free to continue its movement toward a surface to be detected as the transerrer comes to rest and an indicating mechanism actuatable by the detector, said weft detecting mechanism including a resilient member 90 connected at one end to the detector and at the other end to the transerrer arm and having operative engagement at an intermediate point thereof with the carrier for the detector, said resilient member tending 95 to hold the carrier in raised position and the detector in normal position and yieldingly resisting detecting and indicating movement of said detector.

2. In weft detecting mechanism for looms 110 having a regularly moving transerrer arm, a weft detector, a carrier supporting the detector and connected to the transerrer arm for relative movement therewith and free to continue its movement toward a surface to 115 be detected as the transerrer comes to rest and an indicating mechanism actuatable by the detector, said weft detecting mechanism including a spring operatively connected at one end to the detector and at the other end 120 thereof connected to the transerrer arm, and a member upstanding from the carrier and engaging said spring at a point intermediate the ends thereof to divide the same 125 into two sections, one section acting on the detector and the other section acting on the carrier.

3. In weft detecting mechanism for looms 130 having a regularly moving transerrer arm, a weft detector, a carrier supporting the de-

- tector and connected to the transferrer arm for relative movement therewith and free to continue its movement toward a surface to be detected as the transferrer comes to rest and an indicating mechanism actuatable by the detector, said detecting mechanism including resilient means connected at one end to the transferrer arm and at the other end connected to the detector, and means movable with respect to and secured to the carrier to engage a portion of the resilient means and divide the latter into two sections one of which is effective to restore the detector to normal position and the other section of which is effective to restore the carrier to normal position, the last named means being capable of a multiplicity of operative engagements with the resilient means to divide the latter into sections of varying degrees of resilience.
4. In weft detecting mechanism for looms having a regularly moving transferrer arm, a weft detector, a carrier supporting the detector and connected to the transferrer arm for relative movement therewith and free to continue its movement toward a surface to be detected as the transferrer comes to rest and an indicating mechanism actuatable by the detector, said detecting mechanism including a tension spring operatively connected at one end to the transferrer arm and at the other end thereof connected to the detector, a clip adjustably mounted on the carrier and having engagement with one of the coils of the spring, said clip dividing the spring into two sections lying on opposite sides of the clip, one of said sections acting on the detector to restore the latter to normal position and the other section acting on the carrier to move the same to normal position, said clip being capable of engagement with any one of a plurality of coils of the spring for varying the relative resilience of the sections.
- 45 5. In weft detecting mechanism for looms having a regularly moving transferrer arm, a weft detector, a carrier supporting the detector and connected to the transferrer arm for relative movement therewith and free to continue its movement toward a surface to be detected as the transferrer comes to rest and an indicating mechanism actuatable

by the detector, said detecting mechanism including resilient means connected to the transferrer arm and the detector and extending over the carrier and on both sides of the connection thereof with the transferrer arm, said resilient means tending to hold the detector and carrier in normal position relatively to the transferrer arm.

6. In weft detecting mechanism for looms having a regularly moving transferrer arm, a weft detector, a carrier supporting the detector and connected to the transferrer arm for relative movement therewith and free to continue its movement toward a surface to be detected as the transferrer comes to rest and an indicating mechanism actuatable by the detector, said detecting mechanism including a pivoted connection between the carrier and the transferrer arm, and resilient means connected to the transferrer arm and extending on both sides of the pivoted connection in a direction parallel to the surface to be detected, and having operative contact at an intermediate point thereof with the carrier, said resilient means tending to hold the detector and carrier in normal yielding position relatively to the transferrer arm.

7. In weft detecting mechanism for looms having a regularly moving transferrer arm, a weft detector, a carrier supporting the detector and connected to the transferrer arm for relative movement therewith and free to continue its movement toward a surface to be detected as the transferrer comes to rest and an indicating mechanism actuatable by the detector, said weft detecting mechanism including a resilient longitudinal member connected at its ends to the detector and transferrer arm, respectively, and means moving with the carrier and engaging the member to divide the latter into two sections, one to hold the carrier in normal position and the other to hold the detector yieldingly in normal position relatively to the carrier, said member causing the axes of said sections to be oblique with respect to each other.

In testimony whereof I have hereunto affixed my signature.

KENNETH J. UNWIN.
